UNITED STATES PATENT OFFICE.

EDWARD L. FORD, OF YOUNGSTOWN, OHIO.

HEATING FURNACE AND METHOD OF OPERATING THE SAME.

Application filed May 26, 1922. Serial No. 563,756.

To all whom it may concern:

Be it known that I, EDWARD L. FORD, a citizen of the United States, and a resident of Youngstown, in the county of Mahoning and State of Ohio, have invented a new and useful Improvement in Heating Furnaces and Method of Operating the Same, of which the following is a full, clear, and exact description.

10 The present invention relates broadly to billet or ingot heating furnaces, and more particularly to continuous recuperative furnaces for this purpose, and to a method of operating the same.

15 At the present time it is customary in the art to which this invention relates, to heat ingots, billets and the like in continuous furnaces which are usually of the recuperative type. In these furnaces the amount of 20 heat which can be taken up by the billets being heated is only limited by the temperature at which they will stick or weld together. As the billets are usually pushed through the furnace by placing the same 25 directly or indirectly in contact, it has heretofore been customary where welding heats are required, to discharge the billets from the first furnace and recharge the same into a second furnace. This has required the 30 separate heating and maintenance of two different furnaces for bringing each billet to the desired temperature.

35 By the present invention I overcome the heat limitation in a single furnace, and also obviate the necessity of utilizing a plurality of separate furnaces, as has heretofore been done, the billets being raised to a welding temperature in a single furnace.

40 As the present invention may be carried out with a number of different forms of furnaces, it will be understood that the accompanying drawings are illustrative only and are not to be taken as defining the limits of my invention.

45 In the drawings,—

Figure 1 is a horizontal sectional view through one form of furnace, illustrating diagrammatically one embodiment of the present invention; and

50 Figure 2 is a similar view illustrating another embodiment of the invention.

In the form of the invention illustrated in Figure 1, there is provided a furnace 2 having a heating compartment in which is

located a hearth 3, and welding compartments in which are located welding hearths 4. The hearths 4 constitute, in effect, continuations of the heating hearth 3.

The furnace is of the continuous recuperative type, having a charging opening 5 at one end into which the cold metallic bodies, hereinafter referred to generically as billets, are introduced and then fed over the hearth 3 in the direction of the arrow *a*. The flame for heating the billets is directed in any well known manner through the openings 6, and travels in the direction of the arrows *b*, first over the welding hearths 4 and then over the heating hearth 3 in a direction opposite to the travel of the billets thereover. In this manner it will be apparent that there is provided a gradually decreasing temperature from the flame end of the furnace to the charging end.

70 The billets B, in accordance with the usual practice, are pushed over the hearth 3 by the direct contact between the same, as illustrated in the drawings, or by the indirect contact, as shown, for example, in the patent to Nau, No. 694,569, of March 4, 1902. In either case, the feeding is effected by the action of one of the billets on another, and may be continued until such time as the billets reach a temperature at which they tend to weld. At this time it is the practice, 75 where a welding heat is desired, to discharge the billets from the furnace and recharge the same into a separate furnace wherein the temperature is such as to raise the billets to a welding heat. This operation requires two furnaces each of which requires a 80 separate heating system and represents a considerable up-keep factor.

85 In accordance with the present invention, the billets may be discharged from the 90 hearth 3 through the opening 7 just before a welding temperature is reached. They are then immediately recharged onto one or the other of the welding hearths 4 and maintained in spaced relation. This recharging 95 operation may be accomplished by any suitable crane 8 mounted in such manner as to be moved as required to effect the charging operation and to permit the drawing of the billets when a desired temperature has been 100 reached. On the hearths 4 the billets are further subjected to the same source of heat to which they were subjected on the hearth 105

3, but to higher temperature zones, as will be obvious. If desired, the hearths 3 and 4 may be separated by bridge walls 9.

In this form of furnace, and in accordance with this method, the heat limitation in a single furnace is obviated, and it is possible with a single source of heat to economically raise the temperature of the billets to a welding heat. By providing a plurality of hearths 4 it will be apparent that the capacity of the furnace is increased, thereby making it possible to efficiently handle in spaced relation the billets discharged from the heating hearth 3 by the direct action of one of the billets against another.

In Figure 2 there is illustrated a slightly modified form of furnace 2' having therein a continuous hearth constituting a heating portion 3' and a welding portion 4'. The billets B' may be fed over the hearth portion 3' by the direct action of one of the billets against another, as before set forth, this feeding action being continued until the billets reach a temperature just below the welding temperature. They may then be drawn from the furnace by the crane 8' and immediately recharged onto the hearth portion 4' in spaced relation by a crane 8'.

The heating flame may enter the furnace through the opening 6' and travel in the direction of the arrows b', first over the welding hearth 4' and then over the heating hearth 3', whereby the temperature of the billets is gradually raised.

This form of my invention also obviates the heat limitation in a single furnace, and makes it possible to reach a welding temperature with a single source of heat, thereby maintaining all of the advantages of a continuous recuperative furnace.

I claim:

1. In the method of heating billets, the steps consisting in heating a furnace and a furnace extension to provide a gradually varying temperature from end to end thereof, charging the billets into the furnace at the low temperature end, feeding the same through the furnace proper by the direct action of one billet on another, then removing the billets from the furnace and placing them in a manner to minimize wear and

tear on the hearth, in separated positions in the furnace extension to raise the same to a welding heat, substantially as described.

2. In the method of heating billets, the steps consisting in supplying heat to a furnace extension, passing the heat through regions of gradually decreasing temperature to an outlet at the feed-in end of a billet furnace, feeding a row of billets from the low temperature end of the furnace through and out of the furnace proper, and re-charging the billets, in a manner to minimize wear and tear on the hearth, in separated positions in the higher temperature furnace extension, substantially as described.

3. A furnace and a furnace extension having common heating means arranged to heat the extension to a higher temperature than the furnace proper, means for feeding a row of billets through and out of the furnace proper, and means for re-charging the billets in separated positions, in a manner to minimize wear and tear on the hearth, in the furnace extension, substantially as described.

4. The combination with a heating furnace, of two oppositely arranged wing extensions thereon, means for supplying heat to the extensions and passing it through the furnace proper, means for feeding a row of billets through and out of the furnace, and means for re-charging the heated billets in separated positions in the wing extension, substantially as described.

5. In the method of heating billets, the steps consisting in heating a furnace and a furnace extension to provide a gradually varying temperature from end to end thereof, charging the billets into the furnace at the low temperature end, feeding the same through the furnace proper by the direct action of one billet on another, removing the billets from the furnace and moving them to positions outside the furnace extension opposite the positions which they are to occupy in said extension, and then inserting said billets in separated positions in said extension to raise the same to a welding heat, substantially as described.

In testimony whereof I have hereunto set my hand.

EDWARD L. FORD.
